UNITED STATES PATENT OFFICE.

OSKAR LARSON, OF OSAKIS, MINNESOTA.

GRIP FOR PULLEY-COVERINGS.

1,114,775.

Specification of Letters Patent.

Patented Oct. 27, 1914.

Application filed April 19, 1910. Serial No. 556,333.

To all whom it may concern:

Be it known that I, OSKAR LARSON, a citizen of the United States, residing at Osakis, in the county of Douglas and State of 5 Minnesota, have invented certain new and useful Improvements in Grips for Pulley-Coverings, of which the following is a specification.

This invention relates to grips, and more 10 particularly to grips for use in stretching the covers upon pulleys and has for its object to provide a grip which may be used in this connection and which will be arranged to grasp and firmly hold the covering 15 until the latter is secured in position.

Another object is to provide a device of this kind which will be extremely simple and which may thus be produced at a low figure.

Other objects and advantages will be apparent from the following description and it will be understood that changes in the specific structure shown and described may be made within the scope of the claim without departing from the spirit of the invention.

In the drawings forming a portion of this specification and in which like numerals of reference indicate similar parts in the several views, Figure 1 is a perspective view 30 showing the manner of applying the covering to a pulley by means of the present device, Fig. 2 is an enlarged plan of the grip itself, Fig. 3 is a section taken through the gripping jaws.

Referring now to the drawings, the present invention comprises a stationary gripping jaw 5, having upwardly extending ears 6 at its ends, and having extended from its rearward edge a pair of convergent frame 40 members 7, which thus lie at the sides of a triangular opening 8 bounded by these two members 7 and the jaw 5. At the apex of the triangle an opening 9 is provided which receives a ring 10 for the reception of a 45 chain or rope to be employed in connection with the device. Upon a longitudinal line, the jaw 5 is bent to throw its side portions at an obtuse angle to each other, as indicated at 11, and formed in the ears 6 adjacent to the outer ends thereof, there are 50 openings 12, the most forward portions of which are in a common plan with the line 11.

A movable jaw 13 is provided, and has adjacent to one edge and at its ends, a pair of

trunnions 14 which are engaged in the openings 12, the jaw extending in the direction of the jaw 5 normally in a plane at right angles thereto, and as shown, the edge 15 of the jaw 13 which is directed toward the jaw 5, is beveled rearwardly away from the 60 jaw 5 and, at its union with the forward face 13' of the jaw 13, forms a gripping rib 17, and this rib, by reason of the specific location of the openings 12 and the fact that the trunnions 14 lie at points of their peripheries flush with the forward face of the 65 jaw 13, lies in the angle 11. A rearwardly extending handle 18 is carried by the jaw 13, and by means of this handle, the jaw may be rocked upon its pinions to move its 70 rib 17 rearwardly and away from the jaw 5 as shown.

In use, a covering for a pulley, indicated at A, is attached to the pulley at one end and has its other end engaged between the 75 jaws 5 and 13. The handle 18 is then moved toward the plane of the members 7, which brings the jaw 13 into position to securely grip the covering A between the rib 17 and the jaw 5, and by reason of the fact that 80 the forward portion of the jaw 5 is bent upwardly, the covering is securely gripped between the rib 17 and the jaw 5, it being seen from the drawings that, as the jaw 5 is moved forwardly the rib 17 swings in an 85 arc which constantly approaches the upwardly bent forward portion of the jaw 5. It will thus be seen that the greater the pull upon the covering A, the more tightly this 90 covering will be grasped by the grip.

What is claimed is:—

A grip for pulley coverings comprising a V-shaped frame, a transverse member connecting the upper ends of the V-shaped frame, perforated ears extending rearwardly 95 at right angles from either end of the transversely extending member, said transverse member having a lower vertically extending portion, lying in the same plane as the arms of the frame, and an upper portion inclining 100 rearwardly in the direction of the said ears, a blade disposed between the ears and journaled therein, the free end face of said blade inclining toward the inclined portion of the transverse member, a biting rib on one 105 of the longitudinal free edges of the blade, the perforations in said ears being disposed with their centers opposite the angle between

the lower and upper portions of the transverse member, and a handle on the pivotal portion of the blade for swinging the same, said blade being so mounted that the rib is disposed in such relation to the inclined portion of the transverse member that as said blade is swung upwardly said rib will approach closest to the said inclined portion,

thus securely holding the pulley covering between said rib and inclined portion.

10

In testimony whereof I affix my signature, in presence of two witnesses.

OSKAR LARSON.
